FIG. 2.

FIG. 4.

FIG. 6.

UNITED STATES PATENT OFFICE.

LOUIS W. GATES, OF NEW HAVEN, CONNECTICUT, ASSIGNOR TO C. COWLES AND COMPANY, OF NEW HAVEN, CONNECTICUT, A CORPORATION OF CONNECTICUT.

ADJUSTABLE ESCUTCHEON PLATE.

Application filed October 31, 1921. Serial No. 511,568.

To all whom it may concern:

Be it known that I, LOUIS W. GATES, a citizen of the United States, residing at New Haven, county of New Haven, State of Connecticut, have invented an Improvement in Adjustable Escutcheon Plates, of which the following is a specification.

This invention relates to vehicle door locks, and especially to the escutcheon plate 10 and means for mounting the lock operating spindle therein.

An object of the invention is to provide a lock operating spindle with an escutcheon plate which may be adjusted to different 15 angles with respect to the spindle, so that the spindle may be mounted in the door or lock in a horizontal position with the escutcheon fitting snugly against the surface of the door, even though this surface may 20 be curved, or inclined at an angle to the axis of the spindle when mounted in this position.

It is a further object of the invention to provide a simple means for mounting the 25 spindle in the escutcheon, which will allow for comparatively easy fitting and which is not liable to become loose and rattle in operation.

With the foregoing and other objects in 30 view, I have devised structures disclosed in the accompanying drawing, in which—

Fig. 1 is a vertical section through a portion of a vehicle door showing my improved 35 means for mounting the handle applied thereto.

Fig. 2 is a transverse section substantially on the line 2—2 of Fig. 1.

Fig. 3 is a view similar to Fig. 1 showing the device detached from the door but of 40 a slightly modified construction.

Fig. 4 is a transverse section substantially on the line 4—4 of Fig. 3.

Fig. 5 is a view similar to Fig. 3 showing a still further modification, and

Fig. 6 is a transverse section substantially on the line 6—6 of Fig. 5.

The section of the door, represented by the numeral 10, is provided with an opening 11 through which the spindle extends, 50 and in which the conventional lock (not shown) is mounted. The handle 12 is secured to the end of the spindle comprising the usual square portion 13 and the stem 14, and is secured in the door by means of 55 an escutcheon 15 attached to the outer sur-

face thereof by means of suitable screws 16. In the form shown in Fig. 1 the escutcheon has an outwardly extending portion or flange 17 provided on the inner side thereof with a substantially spherical bearing surface 18, and at the inner end of this surface with an annular recess 19 adapted to receive a retaining means 20, also provided with an inner spherical bearing surface 21.

The stem 14 of the spindle is reduced at 65 22 to provide a bearing between two spaced shoulders 23 and 24. Mounted in this reduced bearing, is a bearing member 25 having a spherical outer surface 26 adapted to fit the spherical surface 18 of the 70 escutcheon, and an internal cylindrical bearing surface to receive the bearing 22 of the spindle. This bearing member 25 is split on one side at 27 so that the member may be expanded or compressed a certain 75 amount. In assembling, the bearing 25 is expanded and slipped over the inner enlarged portion 28 of the stem of the spindle, and springs into the annular groove forming the bearing between the shoulders 23 80 and 24. The bearing 25 is then inserted in the spherical bearing surface 18 of the escutcheon, and the retaining ring 20 forced into the recess 19, compressing the bearing 25 somewhat. This ring may be secured in 85 position by any suitable means such as solder 29 or by screw-threads, as shown in Fig. 5.

As the bearing 25 is resilient, it tends to expand in the escutcheon and press its 90 spherical outer surface tightly against the surfaces of the escutcheon and the ring 20, to form a tight fit therewith. This fit, however, allows the escutcheon to have an angular movement on the bearing member when 95 it is applied to a door, to allow for unevenness in or angular arrangement of the door surface. This fit between the bearing member and the escutcheon is sufficiently tight to prevent rotation of the bearing during 100 normal turning movement of the spindle in operating the lock, this turning movement being taken care of by the cylindrical bearing 22 of the spindle in the bearing member 25. As this latter bearing is cylindrical it is much easier to accurately finish than is the spherical surface between the bearing member and the escutcheon, and the bearing for the spindle may, therefore, 105 be much more cheaply and easily fitted than 110

would be the case if the spherical member were rigid with the spindle and rotated within the escutcheon. The cylindrical bearing will also not wear loose as quickly 5 and rattle in operation.

In the modification shown in Figs. 3 and 4, the bearing member 25, the escutcheon 15, and the retaining ring 20 are the same as that illustrated in Figs. 1 and 2. In this 10 form, however, the stem of the spindle is not reduced to form a let-in bearing for the bearing 25, but is formed cylindrical, as shown at 30, on the inner side of the shoulder 24. In this form, the bearing member 15 25 and the escutcheon is secured to the spindle by means of a collar 31 secured to the spindle by any suitable means, such as a set screw or solder 32.

In the form shown in Figs. 1 to 4 the 20 escutcheon is formed by stamping, but in the form shown in Fig. 5 it is preferably a casting indicated at 33. It is provided with an outwardly extending flange 34 provided with a spherical inner surface 35 to receive 25 the spherical bearing member 36, and is provided with an annular recess 37 to receive the retaining ring 38. This ring may be the same as ring 20 in the form shown in Figs. 1 and 3 and soldered in position if desired, but I have shown it as having screw 30 threaded engagement with the recess, and as provided with a transverse groove 39 for engagement of a suitable tool for turning the same to clamp the bearing member in position. The bearing member 36 is also changed somewhat from that shown in Figs. 1 and 4, and instead of being a resilient member split on one side only, it is cut into two or more sections 40. In the particular 40 embodiment shown, these sections are provided with an annular internal rib 41 adapted to seat in the annular groove 42 in the stem of the spindle, so that when in position the spindle cannot have longitudinal 45 movement with respect to the escutcheon. It will be apparent, however, that if desired the spindle may be mounted in the bearing member 36 in either of the ways shown in Figs. 1 and 3, or the spindle shown 50 in Figs. 1 and 3 may be mounted in the manner shown in Fig. 5. The fundamental idea of having a substantially spherical bearing member mounted in a spherical surface within an escutcheon, with some means of retaining it therein to allow angular or rocking movement of the escutcheon with respect to the spindle, but with a substantially cylindrical bearing for the lock operating spindle within the spherical bearing member, to take 55 care of the turning of the spindle during 60 normal operation, being common to all of the forms shown.

Having thus set forth the nature of my invention, what I claim is:

1. In combination, an escutcheon having 65 an opening therethrough, a bearing mounted in said opening for angular adjustment relative to said escutcheon, and a lock spindle mounted to turn in said bearing.

2. In combination, an escutcheon having 70 a substantially spherical recess, a bearing having a substantially spherical surface in said recess and adapted for adjustment therein, and a lock spindle mounted to turn in said bearing. 75

3. In combination, an escutcheon, a bearing having universal adjustment in said escutcheon, and a lock spindle mounted to turn in said bearing.

4. In combination, an escutcheon having 80 an opening therein, a split resilient bearing member mounted in said opening and adapted for angular adjustment therein, and a lock spindle rotatably mounted in said bearing member. 85

5. In combination, an escutcheon having a substantially spherical recess, a resilient split bearing having a substantially spherical surface fitting in said recess, and a lock spindle rotatably mounted in said bearing. 90

6. In combination, an escutcheon having a substantially spherical recess, a resilient, split bearing having a substantially spherical surface fitting in said recess, and a lock spindle rotatably mounted in said bearing 95 and provided with an annular groove adapted to receive a portion of said bearing.

7. In combination, an escutcheon having a substantially spherical recess therein, a bearing member having a substantially spherical surface fitting in said recess, a ring contacting the spherical surface of the bearing member to retain the same in the recess, means for securing the ring to the escutcheon, and a lock spindle rotatably mounted in 105 the bearing member.

8. In combination, an escutcheon, a bearing mounted in said escutcheon and adapted for angular adjustment relative to said escutcheon, and a lock spindle having a substantially cylindrical bearing in said first 110 mentioned bearing and adapted for turning movement therein.

9. In combination, an escutcheon having a substantially spherical recess, a bearing having a substantially spherical surface in said recess and adapted for angular adjustment therein, and a lock spindle having a substantially cylindrical bearing in said first mentioned bearing and adapted for turning 120 movement therein.

In testimony whereof I affix my signature.

LOUIS W. GATES.
